TRACKER MECHANISM FOR MUSICAL INSTRUMENTS

Filed May 20, 1932

UNITED STATES PATENT OFFICE

JOHN T. AUSTIN, OF HARTFORD, CONNECTICUT, ASSIGNOR TO THE AUSTIN ORGAN COMPANY, OF HARTFORD, CONNECTICUT, A CORPORATION OF CONNECTICUT

TRACKER MECHANISM FOR MUSICAL INSTRUMENTS

Application filed May 20, 1932. Serial No. 612,500.

The present invention relates generally to musical instruments of that type having note playing mechanisms employing a tracker bar with openings therein and over which a perforated music sheet passes for controlling the playing mechanisms by predetermined registration of the openings and perforations, and has to do more particularly with the construction, mounting and automatic adjustment of the tracker bar.

An object of the present invention is to improve all prior constructions of adjustable tracker bars and their mountings wherein the tracker bars comprise a plurality of relatively movable sections, such as is shown in my prior United States Patents Nos. 1,099,907 granted June 16th, 1914 and 1,602,369 granted October 5th, 1926.

It is well known that, with the use of music sheets having therein perforations and openings for controlling the playing mechanism, these sheets are subject to changes in width under different climatic conditions, and that the perforations and openings in the sheet, particularly toward the opposite longitudinal edges thereof, vary as to distances between them so that it is difficult to maintain the proper registration of the perforations and openings in the music sheet with the tracker bar openings.

The invention more specifically, therefore, relates to certain improvements in means for automatically adapting the tracker bar to variations in the width of the music sheet.

In prior constructions of this general type, it has been customary to slidably support the sections of the tracker bar upon suitable guide rails, rods or the like, an arrangement which is open to many objections. In the first place, such a structure is a relatively expensive one because of the accuracy and precision necessary in the parts in order to prevent binding and maintain the sections in proper relation. Also, although the greatest care is taken in the manufacture and assembly of such a tracker bar, the same, after it has been in use for some time, does not operate as smoothly and freely as it should because of excessive friction, wear between the parts, and the accumulation of dirt on

the relatively sliding surfaces. Also, due to wear between the relatively sliding surfaces of the tracker bar sections and the supporting members, these sections become loose, and the perforated faces thereof get out of alignment particularly where these faces are vertically disposed, as is usually the case. The result is that the music sheet does not provide the necessary seal as it passes over the several sections, and the proper reproduction of the musical composition by the playing mechanism is materially affected.

Another fault found in prior constructions of sectional tracker bars is that there is a looseness in the pivot joints and connections between the rods, levers and tracker bar sections of the adjusting mechanism, and this looseness naturally increases with wear and use and cannot be readily adjusted or taken taken up, and particularly without throwing the mechanism out of proper balance or registration with the music sheet.

It is, therefore, the purpose of the present invention to provide a sectional tracker bar wherein there are no relatively sliding parts and consequently wherein friction is eliminated; wherein the construction is an open one so that no difficulty may be encountered by the accumulation of dirt in corners, grooves or crevices, and the like; wherein the tracker bar is at all times maintained practically level and cannot fall or move out of alignment; wherein there is no play or lost motion in the operating mechanism; wherein in the tracker sections are supported by rods, or the like, which are always under tension so as to maintain the sections under tension at all times and prevent inaccuracies in the relative positions and alignment of the sections; wherein less power is required for operating the tracker bar sections; and wherein a construction is provided which is considerably cheaper as compared with prior constructions of this general character.

Other objects will be in part obvious and in part pointed out more in detail herein-after.

The invention accordingly consists in the features of construction, combination of ele-

ments and arrangement of parts which will be exemplified in the construction herein-after set forth and the scope of the application of which will be indicated in the appended claims.

In the accompanying drawing:

Figure 1 is a fragmentary front elevation of a tracker bar with its operating mechanisms constructed according to the present invention and shown in relation to a music sheet;

Fig. 2 is a bottom plan view of the tracker bar; and

Fig. 3 is a transverse section taken through the central portion of the tracker bar.

Referring now to the drawing, 10 designates, generally, a tracker bar formed in sections and which, in the present instance, has a middle section 10a which is a fixed section, 20 and the remaining sections are mounted for adjustment toward and away from the middle section. The sections of the tracker bar 10 are supported upon a base board or strip 11 which is mounted in the playing mechanism 25 in any suitable manner and may be fixed against movement or may be connected for adjustment in accordance with various devices used in connection with the playing mechanisms, and which have no relation to the present invention. This bar 11 is provided with pairs of rods 12, two pairs for each section of the tracker bar 10. These rods are shown as being in the form of round wires, but, obviously, they may compose flat 35 strips or ribbons. The rods or arms of each pair may be disposed in transverse alignment with respect to the supporting bar 11 and the outer ends of the rods 12 are secured to the adjacent corner portions of the respective tracker bar section, while the inner ends 40 of the rods 12 are fixed to the supporting bar 11. The rods 12 may be sprung outwardly toward the opposite ends of the tracker bar so that the sections of the tracker bar are urged into spaced apart or extended relation.

As shown particularly in Fig. 3, the supporting bar 11 may be provided at suitable spaced points along its opposite edge portions with socket openings adapted to receive the inner ends of the rods 12, and may also be provided with set screws 13, or the like, for fixing the rods 12 in the socket openings.

The tracker bar 10 is adapted for use in the usual manner and receives thereover a music sheet 14 supported in the usual manner by the playing mechanism and which has the usual note playing perforations, such as designated at 15, for registration with the openings 16 in the tracker bar to control the operation of the playing mechanism.

The middle section 10a of the tracker bar, being a fixed section, has its rods 12 anchored or socketed at their inner ends to the supporting bar 11, and their outer ends connected 65 to the middle section in such manner as to

place the rods 12 under desired tension to hold the middle section rigidly in parallel relation with the supporting bar 11. The mounting of the end sections of the tracker bar 10 is such that they are supported on substantially rectangular frames having a parallelogram movement wherein the tracker bar sections are maintained in parallel relation with the supporting bar or strip 11, and the movement is such that the displacement of the sections out of the front plane of the tracker bar is negligible and is readily taken up by the tension under which the flexible music sheet is operated. Usually, the tracker bars are disposed with their outer ends or music sheet engaging faces in substantially vertical position, and the supporting bar 11 is thus spaced inwardly or rearwardly in a horizontal direction from the tracker bar, and it will be noted that, as the rods 12 are placed under tension and are rigidly connected at opposite ends to the tracker bar sections and to the supporting bar 11, there can be no sagging or dropping of the sections of the tracker bar out of alignment. The sections of the tracker bar are thus yieldingly urged into separated relation, and they are adapted to be moved together when required by the flexing or springing of the rods 12. The rods 12 are of sufficient length, and are so proportioned, as to their inherent strength and resiliency, as to admit of the proper support of the sections and so as not to offer too great resistance to flexing. The tracker bar sections are, therefore, rigidly mounted upon the supporting bar 11 and all sliding, pivoting and other frictional contact parts or surfaces are completely eliminated in this construction.

In accordance with the present invention, the middle section 10a of the tracker bar, so far as variations in the length of the bar are concerned, is fixed against movement, and the sections on opposite sides of this fixed middle section are moved simultaneously but differentially toward the fixed section in the event that the music sheet should contract in width, and are moved simultaneously away from the middle section in the event that the sheet should expand crosswise. To this end, there is provided a lever 17 pivoted, as at 18, to a suitable support beneath or adjacent to the middle section 10a, and which, in the present instance, is disclosed in the form of a plate 19 which may be secured across the lower rods 12 of the middle section. The plate 19 is provided with a central opening 20 of any suitable configuration which registers with the intermediate portion of the lever 17, and the free end of the lever may be offset inwardly to provide a lip 21 adapted for frictional contact against the inner side of the plate 19 to steady the lever 17 in its movement. The pivot 18 of the lever is disposed at the outer end of the plate 19 and is

spaced inwardly from the adjacent end of the lever 17 so as to provide a short arm of the lever outwardly of or beyond the pivot 18. The sections of the tracker bar, to one side of the middle section 10a, are connected by links 22 to the lever 17 at one side of its pivotal point 18, and the sections to the other side of the middle section 10a are connected by links 23 to the lever 17 at the opposite side of its pivotal point 18. Thus, when the lever 17 is turned, the sections of the tracker bar 10 to the left hand side of the fixed middle section 10a will move in one direction, and the sections on the right hand side will move in the opposite direction. It will be noted that the links for the two sections of the tracker bar are connected to the lever 17 at points further removed from the pivot 18 of the lever than are the links connected to the intermediate sections, the object of this arrangement being to cause the outer sections to move greater distances than the intermediate movable sections and thus take care of the accumulated expansion and contraction of the music sheet from the center to the edges thereof. In actual practice, the tracker bar may be made of more than five sections, as shown.

As the rods 12 of the outer sections of the tracker bar 10 normally urge the tracker bar sections to separate or expand, there is a normal tendency exerted upon the lever 17 through the links 22 and 23 to turn the lever 17 in one direction. To counterbalance or neutralize this movement of the lever 17, the lever is provided with a counterbalancing spring 24 which, at one end, is connected to the lever 17 and, at its other end, is anchored to the supporting bar or strip 11 towards one end thereof, as shown in Fig. 2, and the adjacent set screw 13 may be utilized for this purpose.

The spring 24 may be connected to the lever 17 in any suitable manner. In the present instance, one end thereof is connected to the flattened end or lug 25 of an operating rod 26 which is pivotally connected, as at 27, to the free end portion of the lever 17. This spring is so proportioned and is placed under such tension as to substantially counterbalance the spring action of the arms and thus maintain the tracker sections in any position of adjustment until that position of adjustment is disturbed by suitable operating means controlled by the music sheet. This operating means or mechanism may take any suitable form but, by way of illustration only, I have shown, in the accompanying drawing, a mechanism somewhat similar to that illustrated in my Patent No. 1,602,369 dated October 5, 1926. It is understood that this showing is by way of exemplification only and, therefore, the pneumatic arrangement need not be described in detail. It is sufficient to say that the operating means includes a pair

of oppositely acting pneumatics 28 and 29 connected to the rod 26 as through a bar 31, and these pneumatics are associated by suitable tubes 32 and 33 with ports 34 and 35 in one of the end sections of the tracker bar. These tubes 32 and 33 communicate by means of small bleed openings 36 and 37 with an exhaust chamber 39. The note sheet may be provided with a continuous line of spaced perforations or holes 38 which, when the note sheet is properly tracking, will pass over the tracker bar between the ports 34 and 35. It is understood, of course, that, in the event the music sheet should increase in width, the port 35 will be uncovered with the result that the tracker bar sections will be moved farther apart. In the event that the note sheet should become narrower, the line of holes 38 will uncover the port 34, whereupon the pneumatic 29 will turn the lever 17 counterclockwise and, thereby, move the tracker sections towards each other.

It will be observed that, with my improved construction, the tracker bar sections are so supported that friction is entirely eliminated and any danger of dust or foreign matter interfering with the sensitive action of these sections is entirely avoided. Since wear is entirely eliminated, there is no possibility of the introduction of loose play between the sections and, therefore, the accuracy and sensitiveness of the tracker bar are retained throughout the life of the musical instrument in which it is embodied. The arrangement provides a very simple one which can be cheaply manufactured and which requires but very little power or energy in its operation. The sections have a somewhat swinging movement, and this movement is so small as to be simultaneously negligible insofar as the disturbance of the alignment of the perforated surfaces of the sections is concerned, these surfaces being maintained substantially in the same plane at all times so that there is always an effective seal between each of the sections and the note sheet passing thereover. The inherent resiliency of the supporting rods 12 tends to draw the sections apart, and this action is substantially counterbalanced at all times by the spring 24 so that everything is under tension, so to speak, and there is no lost motion between the operating means and the sections. Any wear which may take place in the connections between the operating means and the sections is automatically taken up. More particularly, it will be noted that the inherent resiliency of the rods always exerts a pulling force on the connecting links 22 and 23.

As many changes could be made in the above construction and many apparently widely different embodiments of this invention could be made without departing from the scope thereof, it is intended that all matter contained in the above description or

shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween; for example, the word "rods," as employed in the claims, is intended to include resilient supporting members of various kinds including flat ribbons or strips.

I claim as my invention:

1. In a tracker bar mechanism for musical instruments, a tracker bar comprising a plurality of sections movable lengthwise towards and away from each other, tension means normally urging said sections away from each other, and operating means adapted to be controlled by the music sheet passing over the tracker bar sections for changing the length of said bar.

2. In a tracker bar mechanism for musical instruments, a tracker bar comprising a plurality of sections movable lengthwise towards and away from each other, tension means normally urging said sections away from each other, additional tension means substantially counterbalancing said first tension means, and operating means adapted to be controlled by the music sheet passing over the tracker bar sections for changing the length of said bar.

3. In a tracker bar mechanism for musical instruments, a tracker bar comprising a plurality of sections movable lengthwise towards and away from each other, and tension means for supporting said sections in lengthwise alignment.

4. In a tracker bar mechanism for musical instruments, a tracker bar comprising a plurality of sections movable lengthwise towards and away from each other, tension means for supporting said sections in lengthwise alignment, a spring substantially counterbalancing the tension of said supporting means, and operating means for changing the length of said bar.

5. In a tracker bar mechanism for musical instruments, a tracker bar comprising a plurality of sections movable lengthwise towards and away from each other, and supporting means for said sections comprising resilient rods.

6. In a tracker bar mechanism for musical instruments, a tracker bar comprising a plurality of sections movable lengthwise towards and away from each other, and supporting means for said sections comprising resilient rods, said rods being anchored at one end and being connected at their other ends to the respective sections.

7. In a tracker bar mechanism for musi-

cal instruments, a tracker bar comprising a plurality of sections movable lengthwise towards and away from each other, a fixed support, resilient supporting rods anchored at one end to said support and fixedly connected at their other ends to the respective sections of the bar, and means connected to said rods for changing the length of the bar.

8. In a tracker bar mechanism for musical instruments, a tracker bar comprising a plurality of sections movable lengthwise towards and away from each other, and a plurality of resilient supporting rods each anchored at one end and arranged to support said tracker sections in longitudinal alignment, each of said sections being supported by at least two rods connected to the opposite ends thereof.

9. In a tracker bar mechanism for musical instruments, a tracker bar having a plurality of sections movable lengthwise towards and away from a central fixed section, tension means for supporting said movable sections in substantial alignment and in spaced relation, and means for moving said movable sections towards said central section.

10. In a tracker bar mechanism for musical instruments, a tracker bar having a plurality of sections movable lengthwise towards and away from a central fixed section, resilient supporting rods for said movable sections, and means for flexing said rods to move said sections towards the fixed one.

11. In a tracker bar mechanism for musical instruments, a plurality of lengthwise separable tracker bar sections biased towards relative spread positions, tension means operable on said sections counter to the bias for maintaining the sections under tension in counterbalanced normal relative positions highly sensitive to movement in opposite directions out of their normal positions, and tracker bar lengthening and contracting means controllable by the music sheet to move said sections of the tracker bar towards and away from each other.

12. In a tracker bar mechanism for musical instruments, a supporting strip, a plurality of tracker bar sections spaced from said strip and in substantial alignment with each other, spring arms fixed at opposite ends to the supporting strip and to said sections and arranged to support the sections in longitudinal alignment and in spaced apart relation, a pivoted lever, connections between said sections and the lever and disposed to draw said sections together upon the turning of the lever in one direction and to permit said sections to spread apart under the influence of said arms when the lever is turned in the opposite direction, and tension means connected to said lever and counterbalancing the inherent resiliency of said arms.

JOHN T. AUSTIN.
